ABSTRACT: A novel carburetor arrangement for metering fuel to form a fuel-air mixture for delivery to a spark ignition engine which provides a single fuel-metering system for all engine operating conditions including idling as well as full load conditions. The preferred system features a unique combination of a fluid amplifier with a vortex amplifier for metering liquid fuel and discharging same into the airflow thereby converting an airstream into a uniform fuel-air mixture of substantially constant ratio of fuel-to-air for delivery to the engine.

FLUIDIC-FUEL-METERING SYSTEM

BACKGROUND OF THE INVENTION

This invention relates to a liquid-fuel-metering system for a spark ignition internal combustion engine. More in particular this invention relates to a carburetor construction employing a proportional fluid amplifier in combination with a vortex amplifier serving as liquid fuel discharge and mixing member in a manner wherein the resulting system is singularly capable of supplying fuel to the engine at a substantially constant fuel-to-air ratio for all load conditions imposed upon the engine and still permit the engine to idle without the necessity of a secondary idling fuel system.

It will be noted from the description herein that in the present invention the control of fuel flow to the engine is basically accomplished by a fluid amplifier which proportions or governs the flow rate of fuel according to demand of the engine. The fuel thus metered is initially delivered to a vortex amplifier which serves as a liquid fuel discharge member. The vortex device utilizes a portion of the total air entering the inlet conduit of the carburetor to perform two primary functions; first to take advantage of the swirling movement of the air in the vortex device to mix air with liquid fuel thereby forming an enriched fuel-to-air mixture and, secondly, employing the vortex device to valve the enriched fuel-to-air mixture into the remaining airstream entering the air inlet conduit thereby ensuring a uniform fuel-to-air ratio mixture for delivery to the engine.

The prior art carburetor constructions usually provide two fuel-metering systems of which the first is employed to deliver fuel upstream of the throttle valve during operating conditions imposing a load upon the engine and a second system delivers fuel downstream of the throttle valve for idling engine operating condition. Thus transition from one system to the other system during normal engine operations is required whereas in the present invention such transition is avoided.

U.S. Pat. No. 3,386,710 describes a fuel-metering system employing a fluid amplifier wherein the flow of liquid fuel is split into two streams; one of these two streams discharges through a nozzle directly into the airflow conduit to the engine and the other stream discharges its liquid fuel presumably to a fuel reservoir for recycling. The principal difference is that in the present invention a fuel discharge means to the engine utilizes the advantageous characteristics of a vortex amplifier. Many of the characteristics of vortex devices are well known as, for example, those described in U.S. Pat. No. 3,413,995.

SUMMARY OF THE INVENTION

A principal object of the present invention is to provide a new and improved carburetor for a spark ignition internal combustion engine having a fluidic-fuel-metering means including a fluid amplifier in combination with a vortex fuel discharge device whereby the homogeneity of the fuel-air mixture delivered to the engine is of an improved order over that obtained from carburetors heretofore known.

Another important object of the invention is to provide a carburetor according to the preceding object wherein only one fuel-metering system is employed which singularly is capable of delivering a substantially constant predetermined fuel-to-air ratio mixture for all engine operating conditions.

A further important object of the invention is to provide a carburetor according to any of the preceding objects wherein the fuel-metering requirements are met according to engine demand and accomplished without requiring moving parts for fuel metering.

These and other desirable objects inherent in and encompassed by the invention will become more apparent from the ensuing description of preferred embodiments, the appended claims, and the annexed drawings.

BRIEF DESCRIPTION OF THE DRAWINGS

FIG. 1 is a side view, partly broken away, of the carburetor construction of the present invention showing the position of the vortex device in relation to the air inlet conduit.

FIG. 2 is a plan view of the carburetor of FIG. 1 illustrating, in dotted lines, the configurations of numerous passages.

FIG. 3 is a vertical section, partly broken away, taken on line 3-3 of FIG. 2 showing detailed arrangement of the fluid amplifier and vortex device in the carburetor of the present invention.

FIG. 4 is a plan view of an alternate form of the carburetor wherein the vortex device is positioned downstream with reference to the throttle valve. And,

FIG. 5 is a vertical section taken on line 5-5 of FIG. 4 showing detailed arrangement of the alternate form of the carburetor.

DESCRIPTION OF THE PREFERRED EMBODIMENTS

Referring to the drawing a carburetor of this invention is indicated generally by the numeral 10. The carburetor 10 includes a casing 11 having an upper inlet airflow passage 12. The upper end of the passage 12 is in communication with the atmosphere, usually through a conventional air filter (not shown), and its lower end in communication with the inlet of a vortex device indicated generally by the numeral 13.

The vortex device 13 includes a generally cylindrical-shaped vortex chamber 14 formed in the casing 11 as shown best in FIG. 3. Disposed within the vortex chamber 14 in concentric relation with respect to inlet airflow passage 12 is a shroud indicated generally by the numeral 15. The shroud 15 comprises a cylindrical portion 15a with the upper end 15b thereof frustoconically shaped having an opening 15c therethrough. The lower end portion 15d may conveniently be frustoconically shaped in the form of a skirt as shown in FIG. 3. The entire shroud unit 15 may be supported rigidly within the vortex chamber 14 by the casing 11 through a plurality of suitable support elements 15e shown in FIGS. 1 and 3.

The casing 11 is provided with a flared portion 16 aligned with passage 12 which receives the lower end of skirt 15d of the shroud 15 forming an annular-shaped outlet passage 17 of the vortex device 13 for discharging fluid from the vortex chamber 14 into the upper portion 18 of conduit 19 as best seen in FIG. 3.

Referring again to FIG. 3 it will be seen that the frustoconical-shaped upper end 15b of the shroud 15 forms with the airflow passage 12 an annular-shaped inlet passage 20 communicatively connecting the passage 12 with the vortex chamber 14.

From the forgoing, it will be apparent that a large portion of the air entering through the passage 12 is conducted through the opening 15c of the shroud 15 into the conduit 19 and the balance of the air entering through the passage 12 enters the vortex chamber 14 through the annular-shaped inlet passage 20 and subsequently discharges therefrom into the conduit 19 through the annular-shaped outlet passage 17. It will also be apparent that air from the passage 12 entering the vortex chamber 14 through the annular-shaped inlet passage 20 will not, by virtue of such flow, have a tangential force component and thus such airflow will not be urged into a rotatory motion in the chamber 14. Means will now be described for imparting a tangential force for urging a rotatory or swirling motion of the fluid in the vortex chamber 14 in a counterclockwise direction as viewed in FIG. 2.

In FIGS. 2 and 3 it will be seen that the upper portion of the inlet airflow passage 12 includes an enlargement cut away from the casing 11 to form an aircoop 21. Thus as air moves downwardly in the passage 12 a pressure buildup occurs in the scoop 21. This increased fluid pressure in the scoop 21 is communicated tangentially into the vortex chamber 14 through passage 22 and air discharge nozzle 23; the nozzle 23 being positioned to impart a tangential force in a counterclockwise direction to the fluid in the chamber 14 as is evident from FIG.

2. Thus, air entering the vortex chamber 14 from passage 12 is urged to rotate or swirl in a counterclockwise direction as viewed in FIG. 2. Further, it will be apparent that when the rate of airflow through passage 12 increases, a corresponding increase in the speed of rotation of the fluid in chamber 14 results. As such rotational speed of the fluid in chamber 14 increases, the flow of fluid into chamber 14 through inlet opening 20 and correspondingly discharging through outlet opening 17 progressively decreases. Thus the vortex device 13 acts to valve the flow of fluid therethrough. Theoretically at least, when the speed of rotation of the fluid mass in the chamber 14 approaches infinite, the flow of air into the chamber 14 through inlet opening 20 approaches zero and the discharge flow through the outlet passage 17 approaches the rate of flow through the nozzle 23. The fuel-metering system and its relation to the vortex device 13 will now be described.

In FIG. 3 the numeral 24 indicates generally a fluid amplifier of known construction. The amplifier 24 includes a fuel inlet passage 25 which may have a restriction interposed therein as at 26 and terminating at the interaction zone 27. In the present case liquid fuel 28 from the fuel reservoir 29 is pumped at substantially constant pressure through the pipe 30 and inlet passage 25 to the interaction zone 27 of the fluid amplifier 24 by the pump P. The fluid amplifier 24 is provided with first and second fuel outlets indicated respectively at 31 and 32. The second fuel outlet 32 is directed back to the fuel reservoir 29 through the pipe 33. The first fuel outlet of the amplifier 24 leads to fuel discharge orifices 34,35, positioned as shown in FIGS. 2 and 3, through conduits 36 and 36a. At this point it will be observed from FIG. 2 that the positioning of the fuel discharge orifices 34,35 in the vortex chamber 14 are such to impart a tangential force to the fluid in chamber 14 in a clockwise direction.

The fluid amplifier 24 includes a splitter 37 which permits a division of the flow of liquid fuel 28 entering the interaction zone 27 from the fuel inlet passage 25 to the outlets 31 and 32 according to the pressure differential occurring in signal pressure passage 38 with respect to signal pressure passage 39. Signal pressure passage 38 communicates with conduit 19 through a port 40 opening into the restriction or primary venturi portion 41 of the conduit 19 while the signal pressure passage 39 communicates with conduit 19 through port 42 opening into the conduit 19 upstream of the venturi portion 41 as indicated in FIG. 3. From this it will be apparent that when the engine demand is high as evidenced by a wide-open throttle valve 43, most of the fuel entering the interaction zone 27 of the fluid amplifier will be diverted to outlet 31. Conversely when engine demand is low, as evidenced by an almost closed throttle valve 43, most of the fuel entering the interaction zone 27 of the fluid amplifier 27 is discharged back to the fuel reservoir 29 through outlet 32. From this it will be apparent that the integrated signal pressure values occurring in signal pressure region X (port 40) and signal pressure region Y (port 42) determines the rate or metering of fuel flowing to the discharge orifices 34 and 35. Where the pump P delivers a constant supply at substantially constant pressure then the restriction 26 governs the fuel-to-air ratio for it controls the rate of fuel flow to the amplifier 24. It should further be pointed out that when the pressure values in signal pressure regions X and Y are equal to each other the fluid amplifier should be biased such that all fuel entering the interaction zone 27 is discharged to the reservoir 29 through outlet 32. In short, in order to meter fuel to the discharge orifices 34 and 35 the absolute pressure value in signal pressure region Y must be at least slightly higher than the corresponding absolute pressure value in signal pressure region X.

In FIG. 3 it will be noted that there exists a third signal pressure region Z at the aircoop 21 in the upper inlet airflow passage 12. The absolute pressure value in the signal pressure region Z provides the tangential force component to urge rotatory motion of fluid in the vortex chamber 14 in the counterclockwise direction, as viewed in FIG. 2, indicated previously. However, in the embodiment shown in FIGS. 1-3 the

absolute pressure value in signal pressure region Z does not vary greatly throughout the entire range of engine operation unless, of course, the atmospheric pressure changes. From this it becomes apparent that for a given engine operating condition the integrated pressure values existing in pressure signal regions X, Y and Z govern the operation of the carburetor 10. Further, where the pump P delivers a constant supply of liquid fuel to the fluid amplifier 24 at substantially constant pressure then the restriction 26 governs the fuel-to-air ratio for it controls the rate of fuel flow to the fluid amplifier 24.

In operation of the carburetor 10 control air is diverted from the main airstream flowing in the upper inlet airflow passage 12 into passage 22 for tangential discharge into the vortex chamber 14 through nozzle 23. This flow of control fluid causes the supply airstream entering the vortex chamber 14 through the annular inlet opening 20 to rotate or swirl in a vortex pattern. The vortex flow, because of conservation of angular momentum, results in a decreased pressure at annular outlet opening 17. This is due to the increase in velocity of the fluid in the vortex chamber 14 as the distance of the fluid particles to the outlet 17 decreases. The result of the vortex motion is a decrease in flow through the outlet 17 from an unrestricted flow condition.

As the flow of fuel-air mixture to the engine increases, the flow through the first fuel outlet 31 of the fluid amplifier 24 increases proportionately. Since the fuel discharge orifices 34,35 are positioned to urge rotation of the fluid in the vortex chamber 14 in a clockwise direction (FIG. 2) opposite to that of the nozzle 23 the resultant effect is to slow down the rate of counterclockwise movement of fluid in the vortex chamber 14 which at the same time creates a varying degree of turbulence depending upon the operating condition of the engine. As the fuel flow through fuel discharge orifices 34,35 increases, the amount of swirl of the fluid in the vortex chamber 14 decreases because the pressure signals emanating from fuel discharge orifices 34,35 is countercurrent from that emanating from nozzle 23. Therefore, the flow of enriched fuel-air mixture in the vortex chamber 14 through annular passage 17 to mix with the air passing through opening 15c in the conduit 19 increases as the demand of the engine for fuel-air increases. Furthermore, it will also be apparent that the turbulence in the vortex chamber 14 caused by influx of fuel through the orifices 34,35 improves the vaporization of the enriched fuel-air mixture therein.

While only one nozzle 23 is shown in the drawing, it should be understood that more than one such nozzle may be employed. For example, three of such nozzles 23 may be employed spaced at 120° intervals along the cylindrical periphery of the vortex device 13. Likewise, the drawing illustrates but two fuel discharge orifices 34,35 spaced 180° apart from each other as is evident from FIGS. 2 and 3 whereas, for example, one, three, or more such orifices may be employed.

In the preceding description of one embodiment of the invention illustrated in FIGS. 1 through 3 it will be observed that the vortex device 13 is positioned upstream with reference to the throttle valve 43 and the venturi 41. In an alternate form of the invention as shown in FIGS. 4 and 5 it will be seen that the vortex device 13' is positioned downstream with reference to the venturi 41' and throttle valve 43' which permits the vortex device to function at lower absolute pressure values. In the alternate form it will be seen from FIG. 5 that the control air discharging into the vortex chamber 14 through the nozzle 23 may conveniently be received from air conduit 44 positioned downstream of the venturi 41' through the port 46 and passage 45. In such arrangement it will be noted that the port 46 in the air conduit 44 is positioned above the throttle valve 43'. If desired, the port 46 may alternately be positioned below the throttle valve 43' as at 46' which port would in such case communicate with passage 45 as indicated at 45' in phantom lines in FIG. 5. Of course, the size of the port 46' would be correspondingly larger than that required for alternate port 46 because of the difference in absolute pressure at the position of the port 46 as compared to the position of alternate

port 46' due to the function of the throttle valve 43'. Thus it will be apparent that the signal pressure region Z for the embodiment shown in FIGS. 4 and 5 is different than that for the embodiment shown in FIGS. 1, 2 and 3.

What I claim is:

1. A carburetor for an internal combustion engine comprising:

- a. an airflow means having a venturi disposed therein capable of generating a first signal pressure region and a second signal pressure region adjacent said venturi in air flowing therethrough,
- b. a throttle valve disposed in said airflow means for selectively controlling the rate of air flowing therethrough,
- c. a vortex device having a cylindrically shaped vortex chamber positioned to divert at least a portion of the air flowing in said airflow means through said chamber in bypass relation,
- d. means for urging the air in said vortex chamber into a rotatory movement in one direction,
- e. fuel discharge means for discharging fuel into said vortex chamber positioned to retard the rate of rotatory movement of said air therein,
- f. a proportional fluid amplifier controlled by the integrated pressure values in said first and second signal pressure regions with reference to atmospheric pressure values positioned to deliver and regulate the flow of fuel into said fuel discharge means

whereby an enriched fuel-air mixture is formed in said vortex chamber which mixture is discharged downstream into the remaining portion of said airflow in said airflow means thereby forming a uniform fuel-air mixture having a predetermined ratio of fuel-to-air for delivery to said engine.

2. A carburetor for an internal combustion engine according to claim 1 wherein the vortex device includes a shroud extending into said vortex chamber positioned to conduct therethrough a portion of the air flowing in said airflow means in bypass relation with respect to the air in rotatory movement in said vortex chamber.

3. A carburetor for an internal combustion engine accord-

40

ing to claim 1 wherein the means for urging the air in said vortex chamber into rotatory movement comprises at least one air discharge nozzle communicatively connected through a passage to said airflow means, said nozzle being positioned to discharge a minor flow of air from said airflow means to impart a tangential force to the air in said vortex chamber thereby imparting a rotatory movement in a vortex pattern to the air in said vortex chamber in said one direction.

4. A carburetor for an internal combustion engine according to claim 3 wherein said airflow means includes an aircoop communicatively connected to said air discharge nozzle whereby the pressure of air discharging from said nozzle is increased thereby increasing the rate of rotatory motion of the air in said vortex chamber.

5. A carburetor for an internal combustion engine according to claim 3 wherein said passage connected to said air discharge nozzle is positioned to communicate with said airflow means upstream of said throttle valve.

6. A carburetor for an internal combustion engine accord-

20 ing to claim 1 wherein said fuel discharge means includes at least one fuel discharge orifice communicatively connected through a conduit to a first fuel outlet of said proportional fluid amplifier, said orifice being positioned to discharge fuel into said vortex chamber from said amplifier to impart a tangential force to the air in said vortex chamber in the opposite direction for retarding the rotatory movement of the air in said chamber thereby valving the rate of enriched fuel-air mixture discharged from said chamber into said remaining portion of said airflow in said airflow means.

7. A carburetor for an internal combustion engine according to claim 6 wherein said fuel discharge means comprises two fuel discharge orifices positioned in 180° relation with respect to each other.

8. A carburetor for an internal combustion engine according to claim 1 wherein said vortex device is positioned upstream of said venturi.

9. A carburetor for an internal combustion engine according to claim 1 wherein said vortex device is positioned downstream of said throttle valve.
